UNITED STATES PATENT OFFICE

FRANK L. BAMFORD, OF DETROIT, MICHIGAN, ASSIGNOR TO C. M. HALL LAMP COMPANY, OF DETROIT, MICHIGAN, A CORPORATION OF MICHIGAN

REFLECTOR-GASKET RETAINER

Application filed July 30, 1928. Serial No. 236,314.

The invention relates to vehicle lamps and more particularly to an improved construction for maintaining a seal between the lens and the reflector.

It is usual to provide a cork gasket between the reflector and the lens in order to protect the bright surface of the reflector. These gaskets, however, deteriorate rapidly when in use, particularly, if water is allowed to come in contact therewith as is usually the case when the lamp is exposed to the weather. In such cases the gasket is apt to become broken in removing and assembling the door of the lamp in which case the seal is no longer maintained and the reflector is therefore not protected. It often happens also that the annular cork gasket becomes unseated from the reflector when the door is opened, thereby interfering with the proper closing of the door.

In order to remedy the defects above noted, I have provided an improved construction adapted to maintain the cork gasket in proper position on the reflector and my construction has the advantage that it is simple and cheap to manufacture, although being effective to properly retain the gasket in position.

In the drawings

Figure 1 is a cross section through a headlight provided with my invention;

Figure 2 is a front view of a portion of the reflector showing the gasket retainer in position.

One form of lamp to which my invention is applicable is shown in the accompanying drawings, wherein the lamp body A has mounted therewithin a parabolic reflector B formed of pressed sheet metal. The outer periphery of the reflector has a return bent portion forming an annular wall D substantially parallel to the axis of the reflector. This wall terminates in a transversely extending flange F projecting radially outward and having between the same and the wall D a slightly curved fillet G. H is a substantially flat surface between the curve of the reflector and the wall D.

The door I may be of suitable construction but, as shown, consists of a metallic rim J having the inturned flange K on which is

seated the lens L, it being secured thereto by suitable spring clips M. The door is held in position by suitable means which, as shown, consists of a spring C at the top of the lamp body and a spring clip N engaging a projecting member O on the lamp body at the bottom thereof.

With a construction as above described, it is usual to provide an annular gasket P of a diameter to surround the annular wall D and rest against the flange F. The height of the gasket is slightly greater than the wall D so that the edge of the gasket projects beyond the surface H and is engaged by the inner surface of the lens when the door is in closed position. As heretofore mentioned the gasket will normally be held in the position shown without further supporting means but to guard against accidental displacement when assembling the door and to maintain a seal even after the cork becomes deteriorated, I have provided a gasket retainer R surrounding the outer surface of the gasket and clamping the same against the annular wall D.

This retainer, as shown, consists of a metallic band of a width not greater than the width of the wall D, the band being preferably corrugated throughout its length to provide a certain amount of yieldability. The band is preferably formed from a strip of metal, one end of which has one or more apertures S arranged therein and the other end having a projecting lip T engageable with one of said apertures to complete the ring. The arrangement is such that the band when placed in position upon the gasket places a certain tension on the same, thus maintaining the gasket in proper position.

With the above construction, the effective life of the gasket is considerably extended because even after the material itself becomes hardened and brittle, it is retained in position to maintain a seal and is protected and prevented from breakage by reason of the surrounding resilient band. It will, of course, be understood that while it is preferred to make the gasket retainer in a single strip, the ends of which are secured together in the manner illustrated, the invention is not limited to the precise construction

described but includes within its scope such modifications as would readily be suggested by and which are included within the purview of the appended claims.

5 What I claim as my invention is:

1. In a lamp, the combination of a reflector having a return bent outer flange forming an annular wall and an outwardly extending transverse flange, an annular gasket surrounding said annular wall and projecting beyond the same and a separate retaining ring surrounding said gasket and resiliently bearing against said gasket.
- 10 2. In a lamp, the combination of a reflector having a return bent outer flange forming an annular wall and an outwardly extending transverse flange, an annular gasket surrounding said annular wall and projecting beyond the same and a metallic band surrounding said gasket and having a series of corrugations therein to impart resiliency thereto.
- 15 3. In a lamp, the combination of a reflector having a return bent outer flange forming an annular wall and an outwardly extending transverse flange, an annular gasket surrounding said annular wall and projecting beyond the same and a corrugated resilient metallic band surrounding said gasket, one end of said band having a recess therein and
- 20 the other having a pressed out portion engaging said recess to form a continuous ring resiliently bearing on said gasket.
- 25 4. In a lamp, the combination with a lamp body, a curved reflector secured within said body and having a substantially flat band at the outer edge thereof, said reflector having a return bent portion forming an annular shoulder and having a transverse flange extending radially outward therefrom, a cover engageable with said lamp body, an annular gasket seated on said flange and engageable with said cover and a resilient metallic band corrugated throughout its surface surrounding said gasket, said band being of a normal
- 30 diameter such as to yieldingly press said gasket against said shoulder.
- 35 5. The combination with a lamp reflector having a flange forming an annular wall, a gasket surrounding said wall and projecting beyond the same, and a lamp door movable into and out of engagement with the projecting portion of said gasket, of a resilient band surrounding said wall for clamping said gasket on said wall to prevent accidental dis-
- 40 placement of the same upon movement of said door.

In testimony whereof I affix my signature.
FRANK L. BAMFORD.
